UNITED STATES PATENT OFFICE.

ADOLPH EDWARD VIDAL, OF LONDON, ENGLAND.

TANNING APPARATUS.

SPECIFICATION forming part of Letters Patent No. 656,063, dated August 14, 1900.

Application filed November 14, 1899. Serial No. 736,990. (No model.)

To all whom it may concern:

Be it known that I, ADOLPH EDWARD VIDAL, a subject of the Queen of Great Britain and Ireland, residing at 20 Central Hill, Norwood, 5 London, England, have invented Improvements in Apparatus for Tanning Hides and Skins, (for which I have made application for Letters Patent in Great Britain, No. 25,188, dated November 29, 1898; No. 9,114, dated 10 May 1, 1899; No. 10,385, dated May 17, 1899, and No. 11,314, dated May 31, 1899,) of which the following is a specification.

Various methods have been suggested and put into practical use from time to time for 15 shortening the long and tedious process of tanning hides and skins. These methods may be roughly classed under two heads—chemical, in which the well-known oak-bark was wholly or partially dispensed with and 20 replaced by some other chemical or combination of chemicals, and mechanical, in which the oak-bark was still employed as the tanning agent, but by the use of various mechanical devices, such as forcing the tan liquor 25 through the hide by pressure, it was sought to accelerate the changes taking place in the hide.

My present invention relates to improvements in mechanical methods of tanning, more 30 particularly to frames or gripping devices between which the hides are gripped in order that the tan liquor may be introduced into the space between a folded hide or between 35 hides, so that it may percolate through the pores of the hide, and thus expedite the process of tanning.

With frames hitherto constructed for the above purpose various disadvantages have been encountered, the chief one being that 40 owing to the frames being made with strips between which the hides were gripped, forming a rectangle, (or when the hide was doubled three sides of a rectangle,) a considerable portion of the hide at the tail end had to 45 be cut off or left to remain outside of the frame, thus reducing the size and weight of the tanned butt. Again, it was either necessary to have the frames of various sizes, so as to accommodate different-sized hides or butts, 50 or to make the frames of a comparatively small size, which caused considerable waste when a large butt was tanned. Another de-

fect was that the hide being unsupported in close proximity to the gripping-strips tended to stretch and lose its shape around the edges. 55

To obviate the above-mentioned defects is the purpose of my present invention.

In order to more fully describe my said invention, reference will be first had to the accompanying drawings, in which— 60

Figure 1 shows an elevation of one of the frames which I propose to employ. Fig. 2 shows an end view of same. Fig. 3 represents a transverse section on the line 1 2 of Fig. 1. Fig. 4 is a similar section of two frames 65 clamped together containing a hide or skin. Fig. 5 is an edge view. Figs. 6 and 7 represent longitudinal sections on the line A B, the latter view showing two frames containing a hide clamped together. Fig. 8 is a detail 70 view of the means of clamping two frames together. Fig. 9 shows another form of the gripping-pieces. Fig. 10 is a transverse section of Fig. 9. Fig. 11 represents a section showing the grooved and perforated back 75 board. Fig. 12 shows a method of clamping together a series of frames. Fig. 13 is an enlarged sectional view on the line C D of Fig. 9, showing the gripping edges in detail. Fig. 14 shows another form of my invention, being 80 a longitudinal view, partly in section. Fig. 15 is a side elevation of a portion of the same containing a hide ready to be tanned. Fig. 16 is a transverse section on the line E F of Fig. 14. Fig. 17 is an end view of one of the 85 devices for gripping a hide upon the end pieces, and Fig. 18 is a fragmentary view showing the position assumed when clamped by the clamping devices.

Referring first to the form of my invention 90 shown in Figs. 1 to 8, in these views *f* represents the back boards, which are here shown as being grooved. The purpose of these back boards is to prevent the sagging of the hides while being tanned. Supporting these back 95 boards are the cross-pieces *e*, running cross-wise of the frame. Upon three sides of the said frame beveled strips *c* are provided, these strips being also grooved. Surrounding the outer edge and projecting above the 100 said grooved strips *c* are the gripping-pieces *b*, which are preferably made of brass or other acid-resisting material. *h* represents lugs at one end of the frame, through which

bolts *g* are adapted to pass when the frame is secured together. *i* represents holes through the gripping-pieces on one side of the frame, through which the pipes *k* are adapted to 5 pass for supplying liquor to the inside of the hide when the latter is in position in the frame.

The frames above described are made in pairs in such a manner that when they are 10 superposed the gripping-pieces coincide with one another.

With apparatus constructed as above I proceed as follows: The hides having been prepared in the usual way for the process of tanning, the butt is cut out and folded in, half lengthwise. Its edges are then gripped between a pair of frames, as shown in Fig. 4, and these frames are bolted together, so that the pipes *k* enter between the folded butt. Tan 20 liquor is supplied to one of the pipes *k* from any suitable source of supply that is capable of maintaining a uniform flow, so that the pressure may be constant throughout the tanning operation. I prefer that the pressure 25 shall be slight, as excessive pressure has been found in practice to produce bad leather. On commencing the operation the air-tube is opened and liquor is allowed to enter the bag formed by the folded butt until it is 30 entirely filled, when the air-tube is closed and the lateral pressure causes the liquor to percolate through the pores of the hide.

I prefer to immerse the frames in tan liquor during the process of tanning. In this 35 case the back boards *f* should be perforated, as shown in Fig. 11. Care should be taken that the internal pressure is always in excess of the external pressure, so that the liquid will percolate through the pores of the 40 hide from the inside.

In order to make the frames suitable for various-sized butts, I may make either or both of their ends adjustable.

It has been found preferable to corrugate 45 the surfaces of the beveled portions of the pieces *c*, or in some cases I may fasten thin corrugated brass or other metal not attacked by tannic acid upon bevels with smooth surfaces.

50 The back boards *f* may be formed of wood, metal, or other suitable material, grooved or corrugated. Instead of employing the back boards *f* I may have a backing composed of a material (preferably textile) such as canvas 55 stretched tightly on the frames.

Referring now to the form shown in Figs. 9 to 13, *m m* show the gripping-pieces for gripping a folded hide or butt. It will be seen that the gripping-piece for the tail is 60 shaped to the contour of the tail end of the butt when folded. The said gripping-pieces may be made of metal, wood, glass, or any other suitable material. The inner surfaces of the gripping-pieces *m* are beveled and 65 grooved, so as to allow the liquor to percolate through the portions of the hide or butt coming in contact with these surfaces. *n* shows

lugs formed on the pieces *m m*, provided with holes for bolting the two sets of gripping-pieces together when the folded hide or butt 70 is between them. *o* shows semicircular de-

pressions in the pieces *m*, so placed that when the two pieces *m* are superposed, with the hide or butt between them, a pipe, such as shown in Fig. 4, may be passed through, so as 75 to come in between the folded butt or hide, a similar pipe being provided for the other hole for the exit of air. *r* shows back boards,

which may be similar to those described in connection with Figs. 1 to 8. In using this 80 apparatus the hide is first prepared in the ordinary way for tanning, the offal is cut off, and the remaining butt is folded over lengthwise. The edges are then gripped between the pieces *m m*.

This is effected by placing 85 the pieces in position, one set under the folded butt and the other set over it, so that the edges are gripped between the gripping-pieces *m m*, which are then bolted together tightly. The whole is then suspended in a tank or pit 90 between two of the grooved boards *r*, as shown in Fig. 9. A pipe is then passed through the hole *o* and is connected with the suitable source of supply, and the operation is the same as in the preceding case. In Fig. 11 the 95 boards *r* are perforated as well as grooved, so that when the tank or pit *u* is supplied with tan liquor this liquor will come in contact with the outside of the folded hide. The internal pressure should be in excess of the 100 pressure exerted upon the hide from the liquor in the tank, as in the preceding instance.

The boards *r* are held in position by blocks *w* in such a way that the grooved surfaces may come next to the butts. The liquor 105 which percolates through passes down the grooves and out through the perforations.

During the process of tanning the butts should be taken out in order to examine them and clean out any refuse that may have accumulated. Hides by this process may be tanned 110 in from two to four weeks, according to their thickness.

Although I have stated that the hides or butts are doubled over lengthwise, it is obvious 115 that two open hides or butts may be superposed and gripped between suitably-shaped frames or gripping-pieces; but I prefer to double the hides or butts, so as to economize space and facilitate handling.

According to the form of apparatus shown 120 in Figs. 14 to 18 the process of tanning is precisely the same as that already described; but the gripping-pieces are of circular form, so that when the butt is in position it forms a 125 drum through which the liquor percolates into a tank or pit containing tanning liquor. According to this form of my invention a shaft 1 is mounted in the tank 2. This shaft carries two disks or drum-heads 3 and 4, one of which, 3, is fixed and the other, 4, loose upon the shaft. These drum-heads are connected together by telescopic rods 5. The position of the drum-head 4 upon the shaft 1 is regu-

lated by the nut 6, which screws upon the said shaft. Each of these drum-heads 3 and 4 is formed with a gripping edge 7 around it. The gripping edge 7 on the drum-head 4 is curved to suit the shape of the tail end of the butt. The shaft 1 is hollow and provided with outlets 8, so that liquor may be supplied to the drum. 9 shows a spur-wheel attached to the drum-head 3, by means of which the drum may be rotated from a counter-shaft 10. Figs. 13 and 15 show a ring in two halves to fit over the drum-head 4 and grip the hide onto the gripping edge 7. A similar ring fits over the drum-head 3. 11, Figs. 15 and 17, shows gripping-bars for the side edges of the hide. 12 represents a hollow cylinder, the function of which is to effect an equal distribution of liquor throughout the entire drum formed by the hide with less liquor than would otherwise be required. The mode of operation of this device is as follows: The hides having been prepared for tanning, the offal may be cut off and the butt hung on the rods 5. The side edges of the butt are then gripped between the pieces 11, and the rings 10 are bolted around the disks 3 and 4, so that the two ends are gripped tightly and a drum is formed by the butt. Liquor is then admitted through the shaft 1. Around the drum formed by the butt I propose to fix a covering of wire-gauze or other suitable material, so as to prevent stretching. This wire-gauze is shown attached to the frame containing a butt in Fig. 18 and is indicated by 13.

Having thus described my invention, what I claim, and desire to secure by Letters Patent of the United States, is—

1. In an apparatus for tanning, a gripping-frame composed of parts which may be adjusted relatively to each other, one of said parts being provided with a gripping edge adapted to conform to the shape of the tail end of the hide, substantially as described.

2. In an apparatus for tanning, the combination of a vat, and a gripping-frame supported therein, said frame being composed of parts which may be adjusted relatively to each other, one of said parts being provided with a gripping edge shaped to conform to the shape of the tail end of the hide, whereby

hides of different sizes may be secured in said frame, substantially as described.

3. In an apparatus for tanning, a cylindrical gripping-frame, said frame being provided with closed ends, one of which is shaped to conform to the shape of the tail end of the hide, substantially as described. 55

4. In an apparatus for tanning, the combination of a support, a cylindrical gripping-frame mounted thereon, the ends of said frame being adjustable relatively to each other, substantially as described. 60

5. In an apparatus for tanning, the combination of a supporting-shaft, a cylindrical gripping-frame mounted on said shaft, one of the ends thereof being adjustable and shaped to conform to the shape of the tail end of the hide, and means for supplying tanning liquor to the interior of said frame, substantially as described. 65

6. In an apparatus for tanning, the combination of a hollow shaft provided with openings and a cylindrical gripping-frame mounted on said shaft, substantially as described. 70

7. In an apparatus for tanning, the combination of a hollow shaft, a cylindrical gripping-frame mounted on said shaft, one of the ends of said frame being adjustable in relation to the other, substantially as described. 75

8. In an apparatus for tanning, the combination of a hollow shaft provided with openings, a cylindrical gripping-frame mounted on said shaft, one of the ends of said frame being adjustable and provided with telescoping tubes connecting said ends, substantially 80 as described.

9. In an apparatus for tanning, the combination of a tank, a hollow shaft provided with openings mounted in said tank, means for revolving said shaft, a cylindrical gripping-frame mounted on said shaft, one of the ends of said frame being adjustable on said shaft and shaped to conform to the shape of the tail end of the hide, said frame being provided with telescoping tubes connecting said 90 ends, substantially as described. 95

ADOLPH EDWARD VIDAL.
